KNITTING MACHINE

Ladislaus Robaczynski, Brooklyn, N. Y.

Application March 7, 1935, Serial No. 9,721

8 Claims. (Cl. 66—63)

This invention relates to new and useful improvements in knitting machines and more particularly it pertains to knitting machines of the so-called flat type.

One object of the present invention is to improve the construction and mode of operation of flat type knitting machines and to provide such machines with a novel mechanism by which a wider range or variety of patterns may be obtained than is possible with such machines as they are at present generally constructed.

In certain types of knitting, an ornamental figure or pattern is formed by employing what is generally known in the art as a raised stitch, raised with respect to the main body portion of the fabric. In the production of such patterns, however, the finished fabric generally has upon its rear or reverse side, a relatively long length of yarn commonly known in the art as a float.

Floats are undesirable, since because they are in the form of straight strands or yarns, they have no give and consequently, rob the finished fabric of stretch or give in the direction of the length of the float. Another disadvantage of the float is that it presents long loops which are readily caught by articles of personal wear and broken, and when broken, a puckering or bulging of the fabric results.

A feature of the present invention resides in the provision of a novel construction whereby raised stitch patterns may be produced without the formation of the so-called float.

I am aware that certain machines of the prior art propose to accomplish the afore-mentioned result as for example, the machine illustrated in Patent No. 1,609,325, granted to one, A. Strelz, December 7, 1926. The machine of this patent, as well as all other machines which purport to accomplish this result, with which I am familiar, will produce only the one pattern for which they are set up and when a new or different pattern is desired, the machine must be stopped and set up to produce the new pattern desired. Hence, each change of pattern requires a re-setting of the machine.

The machine illustrated in the Strelz patent heretofore mentioned forms relatively long loops in the fabric, the loops being equal in length to one full round or two rows of ordinary purl stitches. In fabric produced upon this machine, however, the loop or raised stitch is fixed as to location. That is to say, that with any given set up of the machine, the formation of the loop or raised stitch is limited to certain needles and cannot be formed by the needles at will and that

to vary the location of forming the loop or raised stitch on such a machine, the machine must be stopped and reset to produce the loop or raised stitch in the new location desired.

In the Strelz patent referred to, the loops or raised stitches are formed by means attached to certain predetermined needles, which means acts to retract such needles from the knitting position to a non-knitting position and to hold them in the non-knitting position while the remaining needles perform the usual knitting operation. In this machine, all needles would normally perform a knitting operation unless they are provided with the retracting means, in which case the needles provided with the retracting means and such needles only, form the loops or raised stitches and to obtain this loop or raised stitch with other needles, the machine must be reset.

I have found in actual practice that if all needles are normally positioned in a non-knitting position and those needles which are to perform the knitting operation are moved from their normal non-knitting position to the knitting position, the loops or raised stitches being formed by the inoperative needles, I am enabled to select at will the needles to perform the knitting operation and thereby those which form the loops or raised stitches and I am therefore able, not only to locate the loops or raised stitches wherever I may desire, but may also vary at will their length.

A feature of the present invention resides in the provision of a novel mechanism whereby the needles may be selectively moved from an inoperative knitting position to an operative knitting position.

A further feature of the invention resides in the provision of suitable mechanism whereby the several operations of the machine may be carried out automatically.

Other features of the invention relate to certain novel and improved constructions, arrangements and combinations of parts hereinafter described and particularly pointed out in the claims, the advantages of which will be readily understood and appreciated by those skilled in the art.

The invention will be clearly understood from the accompanying drawings illustrating the invention in its preferred form and the following detailed description of the constructions therein shown.

In the drawings,

Figure 1 is a top plan view of the carriage

Figure 12 is a detail transverse sectional view taken substantially on the line 12—12 of Figure 1.

Referring to the drawings by reference character, and more particularly to Figure 1, A designates a knitting machine carriage. The carriage comprises two side members 15 and 16, the member 15 being the rear member of the carriage, the member 16 being the front member 40 of the carriage. Each member comprises a bar 17, and these bars are so positioned with respect to each other that their inner edges designated respectively 18 and 19, are slightly spaced, which space constitutes the knitting position of the machine. Each bar carries on its under face a plurality of cam blocks so arranged with relation to one another that they provide a plurality of channels of irregular form and the side walls of these channels, which 45 side walls are formed by the adjacent side edges of the cam blocks, form the operating means of the needles and their various associated parts to effect a predetermined sequence of operation of the needles.

55 The front member 16 of the carriage is of conventional form. The cam blocks carried by the bar 17, which constitutes the rear member of the carriage are arranged in three groups, each of which groups extends longitudinally of the bar. The inner or foremost group, with respect to the longitudinal center line of the machine, comprises a plurality of cam blocks 20, 21, 22, 23, 24, 25 and 26. Mounted to the rear of these cam blocks 21 to 26, inclusive, there is a plurality of cam blocks 27, 28 and 29. These two groups of cam blocks provide a channel 30 of irregular form which extends longitudinally of the carriage. Mounted to the rear of the cam blocks 27 to 29, inclusive, there is another group 60 comprising cam blocks 31, 32, 33, 34, 35 and 36, and these latter cam blocks 31 through 36, inclusive, together with the cam blocks 27 through 29, inclusive, provide a channel 37, which latter channel lies to the rear of the channel 30 and extends substantially throughout the length 75

of the side member 15. The reference character 38 designates a branch channel leading from the channel 30, and extending forwardly thereof. This branch channel 38 is connected at its ends to the channel 30, at which points it has 5 communication therewith and is formed by a cam block 39 positioned to the rear of and slightly spaced with relation to the cam block 23 herefore mentioned. By reference to Figure 1, it will be noted that the channels 30 and 38 extend 10 around the cam block 39 and that the branch channel 38 is located forwardly of the channel 30 with respect to the longitudinal center line 15 of the carriage. Mounted opposite the right hand end of the branch channel 38 in Figure 1, 15 there is a cam block 40, and mounted opposite the left hand end of the branch channel 38 in Figure 1, there is a cam block 41. These two cam blocks 40 and 41 are extensible and retractable, and when in their retracted position, 20 their outer face is flush with the top wall of the channel 30, in which position the cam blocks are ineffective.

Mechanism is provided to retract and extend these cam blocks alternately. That is to say, 25 that when either block is in its extended position the other block will be retracted. It will be noted that when either block is in its extended position, it forms a portion of the wall 30 of the channel 30, and when in its retracted position its corresponding cam block 28 will form the wall of the channel. Thus, the extensible and retractable cam blocks 40 and 41 alter the shape of the channel 30 between the cam blocks 22 and 28, and 24 and 28 for a purpose to be 35 hereinafter described.

Mechanism by which these cam blocks are operated is more clearly shown in Figures 3 to 7. In Figure 5 it will be noted that each cam block is provided with a vertically extending standard 40 45. This standard is notched as at 46, and between the end walls of the notched portion 46, there is a cam member 47. These cam blocks 40 and 41 are slidably mounted as at 48 in a plate 49 suitably mounted upon the carriage and slidably mounted beneath this plate 49 there is a cam member 50. This cam member 50 is so arranged that it has spaced inclined faces 51 and 52 at one end and 53 and 54 at the other end and it is carried by a reciprocating bar 55, it being connected thereto by a suitable plate or the like 56. The reciprocating bar 55 has a series of notches 57, 58, 59 and 60, and adapted for engagement with these notches there is a spring 61, the tension of which may be adjusted 55 by a screw or bolt 62, mounted in a bracket 63 suitably secured to the carriage. By means, not shown, but which may be chain controlled in a manner which is common to the control of various elements of this type of machine, the reciprocation of the bar 55 is effected as the carriage reaches each end of its traversing movement. For example, with the parts in the position in which they are shown in Figure 1 and with the carriage moving to the left in said figure, the 65 cam 41 will be extended and the cam 40 retracted. As the carriage reaches the end of its traversing movement to the left, the bar 55 will be reciprocated to the right in Figure 3, which operation will cause the inclined face 52, of the member 50 to ride beneath the cam member 47 of the cam block 41 and elevate the same. At the same time, the cam face 53 of the member 50 will engage the upper face of the cam member 47 of the cam block 40 and depress or extend 70 75

said cam block 40. This position of the bar 55 is shown in dotted lines in Figure 3. The carriage now moves to the right in Figure 1 and as it reaches the end of its movement in this direction, the bar 55 will be reciprocated to the left, in which position it is shown in full lines in Figure 3 and this movement of the bar will cause the cam face 51 of the member 50 to engage the upper face of the cam member 41 of the cam block 41 to move said cam block 41 to its extended position, and the cam face 54 of the member 50 will engage beneath the cam member 41 of the cam block 40 to move said cam block 40 to its retracted position. Thus it will be apparent that depending upon the direction of travel of the carriage, the leading cam block of the cam blocks 40 and 41 will be extended while the trailing cam block will be retracted. To retain the operating bar 55 in the position to which it is moved at the end of each stroke, the spring 61 is adapted to engage in one position, the notches 57 and 59, and in the other position, the notches 58 and 60.

In the accompanying drawings, the needles, which are of the so-called double latch type, are designated by the reference character 70, and as best illustrated in Figure 7, these needles are slideable in channels 71 in needle beds directly beneath the carriage. It is to be understood that in machines of this type there are two needle beds which are spaced from each other, the space between the needle beds being directly below the space between the adjacent edges 18 and 19 of the side bars of the carriage, and that during the knitting operation the needles may be transferred from time to time, from the channels in one bed to the channels in the other bed, which transfer of needles is effected in the well-known manner by jacks 74 in the rear bed and jacks 75 in the front bed, which latter, by the way, is herein illustrated as of conventional form. As best illustrated in Figures 9 to 12, inclusive, these jacks 74 and 75 have projections or butts 76, and are moved longitudinally of their respective channels in the needle beds by passage of said butts through the channels formed by the various cam blocks of the carriage in a manner to be hereinafter described. The needle beds are so formed that the forward ends of the needle channels with respect to the longitudinal center line of the machine, are provided with teeth 77, as best seen in Figures 9 to 12, and it is between the adjacent edges of these teeth that the yarn is laid upon the open latches of the needles during a knitting operation. It will, therefore, be seen that if the needles are positioned across the space between the needle beds so that their latches receive a yarn as it is laid and the needles again retracted or transferred to the other bed, a knitting operation will be effected. These positions of the needles are illustrated in Figures 9 to 11. If, however, a needle is held retracted with its hooked end positioned between the teeth 77 of the channel in which it is mounted, in which position a needle is illustrated in Figure 12, the needle will not receive the yarn as it is laid and therefore, will not effect a knitting operation but will merely remain idle holding the stitch previously formed upon the needle.

Referring to Figure 8, the several stitches designated B are those which are formed by the knitting operation and in the illustration are of the type known as, "purl" stitch. It will be noted in the said illustration that certain stitches, for example, those designated C, are longer than the

stitches B, their length being equal to two courses or one complete round, which constitutes two rows of stitches B, and these stitches or loops C are formed by those needles which, as shown in Figure 12 of the drawings, lie idle behind the teeth 77 of the needle bed in which they are mounted, while a yarn is laid in the needles which are to effect the knitting operation. While in the present illustration these stitches or loops C have been shown of a size equal to two rows of stitches or one complete round, they may be of any desired length, as will be hereinafter described.

As heretofore stated, to effect the knitting operation, the needles must be extended across the space between the needle beds and this is the function of the branch channel 38. By reference to Figure 1, it will be noted that if the butts of the needle jacks are introduced into the branch channel 38, the needle jacks will move the needles forwardly with respect to the longitudinal center line of the machine to position the needles across the space between the needle beds and thereby effect a knitting operation. If, however, the butts of the needle jacks traverse the channel 30, passing to the rear of the cam block 39, they do not enter the branch channel 38, and the jacks and needles will be held retracted in the position in which they are illustrated in Figure 12, and those needles which are retained in the retracted position will not receive a yarn but will merely hold the stitch previously formed thereon to form the long stitches or loops C in Figure 8, while the remaining needles perform the knitting operation.

From the foregoing it will be apparent that with the present device, that all the needles, were their jacks to pass through the channel 30, would be inoperative to effect a knitting operation and therefore, some means must be provided to move the jacks and needles forwardly to the knitting position. In the present embodiment of the invention this means consists of jack pushers designated 78 in the drawings, and by reference to Figures 9 to 12, inclusive, it will be seen that these jack pushers each have a butt 79 projecting from their upper edge at the forward end thereof. The butts of these jack pushers are adapted to ride through the channel 31, or maintain a position at the rear of the cam blocks 31 to 36. These pushers, therefore, by reason of their engagement with the jacks, operate to select those needles which are to perform the knitting operation, and this operation will now be described.

In Figure 1 of the drawings, I have illustrated two needles, one of which is to perform the knitting operation, the other needle to remain retracted and hold the stitch previously formed thereon in order that a relatively long loop or stitch such as C, may be formed. In Figure 1 it is to be assumed that the carriage is moving towards the left, in which case the cam block 41 will be extended and the cam block 40 retracted in the manner heretofore described. For the sake of illustration, the two needles will be designated 80 and 81, the needle 80 being that needle which performs the knitting operation, and the needle 81 being that needle which operates to retain the stitch previously formed thereon and which is held retracted so that it does not receive a yarn during the yarn laying operation. As the carriage moves to the left in said figure, the butts of the jacks will engage the edge 83 of the cam block 41 and will be directed through the channel 30 to a point opposite the entrance to the

branch channel 38. During this operation the butt 79 of that pusher 78 which is positioned at the rear of the jack of the needle 80, is travelling through the channel 37, and immediately the butt 16 of said jack behind the needle 80 is in the position opposite the entrance to the branch channel 38, the pusher by reason of engagement of its butt with the wall 84 of the channel 37, will move forward and introduce the butt of the 10 needle jack behind the needle 80 into the branch channel 38, whereupon the branch channel, by reason of its shape, will move the jack forwardly, thus moving the needle to knitting position and out of engagement with the jack pusher 78, as 15 illustrated in the third position reading from the left in Figure 1. During this operation, the pusher 78 to the rear of the jack of the needle 81 not having been moved forward, has its butt positioned behind the cams 31 to 36, inclusive, 20 and therefore not travelling through the channel 37, does not engage the rear of the jack 74 behind said needle 81, and therefore the jack 74 behind the needle 81 travels through the channel 30, passing to the rear of the cam block 39, 25 to move the needle 81 to the retracted position shown in the third position reading from the left in Figure 1, and illustrated also in Figure 12, in which position it will not receive the laid yarn, and therefore, will not effect a knitting operation 30 but will merely hold the stitch previously formed thereon.

While I have not shown any means for moving the pushers 78 forwardly to a position where they may be picked up by the channel 37, I have in 35 actual practice used ordinary jacquard cards operated in a conventional manner to selectively move the jack pushers forwardly into the position where they will be picked up by the channel 37 and cause to operate the jacks to move the 40 selected needles to the knitting position. Thus it will be seen that by the provision of suitable jacquard cards, those needles upon which the longer stitches or loops are to be formed may be selected and thus the long stitches or loops 45 may be formed at any location desired in the finished fabric.

While I am aware of the fact that a fabric similar in many respects to that shown in Figure 8, has heretofore been formed upon machines of 50 this type, so far as I am aware, the larger loops or stitches designated C in said Figure 8, cannot be selectively located in the fabric. This is because of the fact that in the machines of the prior art, the needles normally traverse a knitting 55 course and are held in retracted position when the loops or large stitches are desired. To retract the needles and needle jacks from a normal knitting position to a non-knitting position requires a pull upon the needles, and therefore the 60 needle jack operators were attached to the jacks and only those needles which had the operators attached to the jacks could be retracted to non-knitting position, therefore limiting the number 65 of needles upon which the larger loops or stitches C could be formed.

In the present mechanism, however, all of the 70 needles would normally travel a non-knitting course and are pushed forwardly into knitting position. For example, if none of the jack pushers were moved to a position where they would be picked up by the channel 37, the butts of the 75 needle jacks would pass through the channel 30 and would not enter the branch channel 38, and therefore, would not perform a knitting operation. By this arrangement and construction, it

is apparent that the knitting operation may be performed selectively upon the needles and that in so doing, any desired needles may be held inoperative, and therefore, may be caused selectively to form the longer stitches or loops C, and therefore, these loops may be formed at any position in the finished fabric. By the same token, these loops may be of any desired length since the needles upon which they are formed may be held retracted for two or more courses or 10 two or more rounds and may be thrown into operation at any time merely by the operation of the jack pushers by a suitable jacquard mechanism.

Having thus described the invention, what is 15 claimed as new, is:

1. In a knitting machine having mutually adjacent flat needle beds and a carriage slidable over said needle beds, needles slidable in said needle beds, jacks slidable in said needle beds, butts on said jacks, a plurality of stationary cam blocks carried by said carriage and forming a plurality of spaced continuous channels upon the under face of the carriage, which channels extend substantially throughout the length of the carriage, and one of which is adapted to receive the butts of the jacks to retain the needles retracted in a non-knitting position, a branch channel leading from that channel through which the jack butts pass, said branch channel communicating at its ends with said channel and being adapted to receive the butts of the jacks to advance the needles to a knitting position, extensible and retractable cam blocks for engagement with the butts of the jacks to advance the jacks to a 35 position where their butts may enter the branch channel, and means for introducing the butts of the jacks into said branch channel.

2. In a knitting machine having mutually adjacent flat needle beds and a carriage slidable over said needle beds, needles slidable in said needle beds, jacks slidable in said needle beds, butts on said jacks, a plurality of stationary cam blocks carried by said carriage and forming a plurality of spaced continuous channels upon the under face of the carriage, which channels extend substantially throughout the length of the carriage, and one of which is adapted to receive the butts of the jacks to retain the needles retracted in a non-knitting position, a branch channel leading from that channel through which the jack butts pass, said branch channel communicating at its ends with said channel and being adapted to receive the butts of the jacks to advance the needles to a knitting position, extensible and retractable cam blocks for engagement with the butts of the jacks to advance the jacks to a 45 position where their butts may enter the branch channel, and means for introducing the butts of the jacks into said branch channel.

3. In a knitting machine having mutually adjacent flat needle beds and a carriage slidable over said needle beds, needles slidable in said needle beds, jacks slidable in said needle beds, butts on 65 said jacks, a plurality of stationary cam blocks carried by said carriage and forming a plurality of spaced continuous channels upon the under face of the carriage, which channels extend substantially throughout the length of the carriage, 70 and one of which is adapted to receive the butts of the jacks to retain the needles retracted in a non-knitting position, a branch channel leading from that channel through which the jack butts pass, said branch channel communicating at its 75

ends with said channel and being adapted to receive the butts of the jacks to advance the needles to a knitting position, extensible and retractible cam blocks for engagement with the butts of the jacks to advance the jacks to a position where their butts may enter the branch channel, means for alternately extending and retracting said extensible and retractible cam blocks, and selectively operated means for introducing the butts of the jacks into said branch channel.

4. In a knitting machine having mutually adjacent flat needle beds and a carriage slidable over said needle beds, needles slidable in said needle beds, jacks slidable in said needle beds, butts on said jacks, a plurality of stationary cam blocks carried by said carriage and forming a plurality of spaced continuous channels upon the under face of the carriage, which channels extend substantially throughout the length of the carriage, and one of which is adapted to receive the butts of the jacks to retain the needles retracted in a non-knitting position, a branch channel leading from that channel through which the jack butts pass, said branch channel communicating at its ends with said channel and being adapted to receive the butts of the jacks to advance the needles to a knitting position, extensible and retractible cam blocks for engagement with the butts of the jacks to advance the jacks to a position where their butts may enter the branch channel, automatic means for alternately extending and retracting said extensible and retractible cam blocks, and selectively operated means for introducing the butts of the jacks into said branch channel.

5. In a knitting machine having mutually adjacent flat needle beds and a carriage slidable over said needle beds, needles slidable in said needle beds, jacks slidable in said needle beds, butts on said jacks, a plurality of stationary cam blocks carried by said carriage and forming a plurality of spaced continuous channels upon the under face of the carriage, which channels extend substantially throughout the length of the carriage, and one of which is adapted to receive the butts of the jacks to retain the needles retracted in a non-knitting position, a branch channel leading from that channel through which the jack butts pass, said branch channel communicating at its ends with said channel and being adapted to receive the butts of the jacks to advance the needles to a knitting position, extensible and retractible cam blocks for engagement with the butts of the jacks to advance the jacks to a position where their butts may enter the branch channel, means operable at the end of each traverse movement of the carriage for alternately extending and retracting said extensible and retractible cam blocks, and selectively operated means for introducing the butts of the jacks into said branch channel.

6. In a knitting machine having mutually adjacent flat needle beds and a carriage slidable over said needle beds, needles slidable in said needle beds, jacks slidable in said needle beds, butts on said jacks, a plurality of stationary cam blocks carried by said carriage and forming a plurality of spaced continuous channels upon the under face of the carriage, which channels extend substantially throughout the length of the carriage, and one of which is adapted to receive the butts of the jacks to retain the needles retracted in a non-knitting position, a branch channel leading from that channel through which the jack butts

pass, said branch channel communicating at its ends with said channel and being adapted to receive the butts of the jacks to advance the needles to a knitting position, extensible and retractible cam blocks for engagement with the butts of the jacks to advance the jacks to a position where their butts may enter the branch channel, automatically operating means, operable at the end of each traverse movement of the carriage for alternately extending and retracting said extensible and retractible cam blocks, and selectively operated means for introducing the butts of the jacks into said branch channel.

7. In a knitting machine having mutually adjacent needle beds and a carriage slidable over said needle beds, needles slidable in said needle beds, jacks slidable in one of said needle beds, butts on said jacks, butts on said jack pushers, a plurality of stationary cam blocks carried by said carriage and forming a pair of spaced channels one of which is forward of the other with relation to the longitudinal center line of the machine, the foremost of said channels being adapted to receive the butts of the jacks and the rear channel being adapted to receive the butts of the jack pushers, a branch channel leading from the foremost of said channels and having communication therewith at each end of the branch channel, said branch channel being adapted to receive the butts of the needles to move the same to effect a knitting operation, the butts of the jacks being introduced into the branch channel by the jack pushers, and means for positioning the butts of the jacks alternately opposite to the ends of the branch channel in opposite directions of movement of the carriage to permit of their introduction into the branch channel by the jack pushers, said last mentioned means comprising cam blocks movable into and out of position in the foremost of said channels and located at the ends of said branch channel.

8. In a knitting machine having mutually adjacent needle beds and a carriage slidable over said needle beds, needles slidable in said needle beds, jacks slidable in one of said needle beds, butts on said jacks, butts on said jack pushers, a plurality of stationary cam blocks carried by said carriage and forming a pair of spaced channels one of which is forward of the other with relation to the longitudinal center line of the machine, the foremost of said channels being adapted to receive the butts of the jacks and the rear channel being adapted to receive the butts of the jack pushers, a branch channel leading from the foremost of said channels and having communication therewith at each end of the branch channel, said branch channel being adapted to receive the butts of the needles to move the same to effect a knitting operation, the butts of the jacks being introduced into the branch channel by the jack pushers, and means for positioning the butts of the jacks alternately opposite to the ends of the branch channel in opposite directions of movement of the carriage to permit of their introduction into the branch channel by the jack pushers, said last mentioned means comprising cam blocks alternately movable into and out of position in the foremost of said channels and located at the ends of the branch channel and means for automatically operating said cam blocks.
